UNITED STATES PATENT OFFICE.

HENRY G. FRENCH, OF SCHENECTADY, NEW YORK, ASSIGNOR TO GENERAL ELECTRIC COMPANY, A CORPORATION OF NEW YORK.

LOCKING DEVICE FOR SWITCHES.

1,119,590.

Specification of Letters Patent.

Patented Dec. 1, 1914.

Application filed June 22, 1912. Serial No. 705,185.

To all whom it may concern:

Be it known that I, HENRY G. FRENCH, a citizen of the United States, residing at Schenectady, county of Schenectady, State of New York, have invented certain new and useful improvements in Locking Devices for Switches, of which the following is a specification.

My invention relates to electric switches 10 and more particularly to locking devices for preventing accidental opening of electric switches.

Some forms of electric switches, particularly disconnecting switches of the knife blade type, are usually operated by means of a wooden operating rod which has on one end, a hook for engaging an opening or eye in the blade or movable member of the switch. Switches of this type, particularly 20 knife blade disconnecting switches, are apt to be forced open by the very heavy rush of current caused by a severe short circuit and when opened in this manner may cause considerable damage by arcing. Disconnecting switches should therefore be provided with 25 a locking device for preventing accidental opening. Spring pressed latches for holding the switch closed have been proposed, but great difficulty is encountered in using the 30 wooden operating rod to hold a spring pressed latch of the ordinary type out of the way of the switch blade and also at the same time to move the switch blade. Disconnecting switches are often so mounted that the 35 blade swings from a horizontal position downward into a jaw contact when the switch is to be closed. When such a switch is open the blade tends to swing downward by its own weight and some holding means 40 or stop should be provided which will prevent accidental closing of the switch by the weight of the blade but which can easily be moved out of the way by the operating rod.

The object of my invention is to provide 45 for electric switches, particularly disconnecting switches of the knife blade type, a holding device which will stop and hold the switch blade in a predetermined relation to the contact jaws; which will prevent accidental closing of the switch; which will automatically lock the switch closed and thereby prevent accidental opening of it; which can easily be set by means of the operating rod in a position to permit the blade to move

or the switch to open and will remain set and 55 not interfere with the movement of the switch blade; which automatically returns to normal or latching position before the switch is again operated, so that when the switch is again closed, for example, the locking device automatically catches and holds 60 it; which can be applied to any standard disconnecting switch, without requiring changes in the jaw contacts or insulators; and which is in general in many details hereinafter 65 more fully set forth, an improvement in devices of this character.

My invention will best be understood in connection with the accompanying drawing, which shows merely for illustration some of 70 the various forms in which my invention may be embodied and in which—

Figure 1 is a side view in elevation of a knife blade disconnecting switch with a locking device embodying my invention applied 75 to it; Fig. 2 is a cross section on the line a—a through the blade of the disconnecting switch showing the locking device in elevation and in the locking position; Fig. 3 is a sectional view along the same line showing 80 the locking device set in a releasing position to permit the switch to open without hindrance and with the switch blade moved a slight extent in a direction to open the switch; Fig. 4 is a modified form of my invention shown in position to hold the switch 85 closed; Fig. 5 is a view of the same modification in a position to permit the switch to open; Fig. 6 is a side view of a modification for preventing accidental closing of a switch 90 such as a double throw switch; Fig. 7 is a plan view of the device of Fig. 6; Fig. 8 is a sectional view along the line 8—8 of Fig. 7; and Fig. 9 is a sectional view along the same line with some of the parts moved to 95 release the blade.

The disconnecting switch shown in the drawing is mounted upon suitable insulators 1 and comprises a jaw contact 2 mounted on one insulator, a jaw contact 3 mounted on the other insulator, and a blade 4 pivoted in the jaw 3 to coöperate with the other jaw 2. The blade 4 has in one end an eye 5 in which the hook on the end of the wooden operating rod is inserted when the operator desires to 100 open or close the switch.

In accordance with my invention as embodied in Figs. 1, 2 and 3, accidental open-

ing of the disconnecting switch is prevented by means of a locking device comprising two arms or latches 6, one on each side of the blade 4 and biased or pressed in any suitable way, as by a spring, to locking position for holding the switch closed. These latches are provided with shoulders 7 for engaging the blade 4 to hold the switch closed, and have flaring extensions 8 which enable the operator 5 to easily move the latches 6 out of the latching position shown in Fig. 2, and into the releasing position shown in Fig. 3, by means of the wooden operating rod. The two latches have a common pivot 9, which is carried 10 by a suitable support 10 mounted near the jaw 2. This support 10 is a flat plate which can be inserted beneath the jaw contact of any standard disconnecting switch without requiring any changes in the contact 15 or in the insulator, so that my invention may be applied to any standard switch with a minimum of trouble and expense. If the latches 6 are pushed back into the releasing position while the switch is closed, they should 20 remain there. To accomplish this result, I provide some suitable means which will, as long as the switch is closed, automatically catch and hold each latch in the releasing position when it is pushed back into that position, shown in Fig. 3, but which will not catch when the latches are pushed back by the blade 4 entering between them as the switch is being closed. The particular means shown in the drawings for 25 holding back each latch is a setting pawl or dog 11 pivoted on each latch 6 and arranged to catch on the blade 4 and thereby hold back the latches 6 as long as the blade 4 is in the clip 2. The setting pawl 11 is biased 30 to move upward against a shoulder 12 on the latch 6 into a position in which its inner end engages the blade 4 when the switch is closed, and thereby holds the latch 6 back in the releasing or inoperative position with 35 its shoulder 7 out of alignment with the blade 4. As shown in the drawings, these pawls or dogs 11 project toward each other, and their inner ends engage the opposite sides of the blade 4 when both latches 6 are 40 held back in the releasing position shown in Fig. 2. The latches 6 are biased toward each other and into latching position by any suitable means, such as springs 13. These springs also engage the pawls 11 to force 45 them upward against the shoulders 12, so that in this position, the latches 6 and pawls 11 form practically a single unit pivoted at 9. As a result of this construction the springs 13 not only move the pawls 11 into 50 the position shown in Fig. 3 but also tend to turn the latches 6 about their pivots 9. The springs 13 are mounted in sockets or recesses 14 and push upward against caps 15 which engage the pawls 11. This arrangement 55 is compact, convenient, and protects the spring, but many other arrangements can be used to obtain the same results. As the switch opens and as soon as the blade 4 passes out from between the inner ends of the pawls, the springs 13 throw the latches 6 in against the sides of the blade 4. The further opening of the switch is not hindered except by the friction of the latches against the sides of the outwardly moving blade, but as soon as the blade passes out from between them, the latches spring into the position of Fig. 2, ready to catch and hold the blade 4 when the switch is again closed. 60 The operation of the device is as follows: As the switch is closed and the blade 4 moves toward the clip 2 the blade engages and forces apart the latches 6 passing between them and into the clip 2 until finally it reaches the position shown in Fig. 2, 65 whereupon the spring pressed latches 6 snap in behind the blade into the latching position, and the blade 4 is held by the shoulders 7 of the latches. When the operator desires to open the switch he pushes one of the latches 6 back out of the way by pushing with the end of the operating rod against the extension 8 of the latch. As the latch 75 swings back on the pivot 9 into the releasing position, the inner end of the pawl 11 is carried out from beneath the blade and then 80 swings under the influence of the springs upward along the side of the blade until it engages with the shoulder 12. This upward movement of the pawl 11 brings its inner end into position to engage the side of the blade 4, and thereby lock the latch 6 in the releasing position shown in Fig. 3. The other latch 6 is then pushed back into the releasing position, whereupon the other 85 pawl 11 swings up against its shoulder 12 and likewise holds the other latch in the releasing position. As a result of this operation both the latches 6 are held or set in the releasing position shown in Fig. 3 with the shoulders 7 out of alignment with the blade 4, so that the switch can be opened 90 without hindrance from the latches. The operator then inserts the hook of the operating rod in the eye 5 of the blade 4 and begins to pull the blade 4 out of the clip 2. As the blade 4 moves out from between the latches 6 it passes from between the pawls 11, whereupon the latches 6 are free to return to latching position under the influence of the spring 13. With the parts proportioned as shown in the drawing the latches 6 cannot return to the position shown in Fig. 2 immediately upon the escape of the blade 4 from between the pawls 11 because the blade 4 is still between the latches, but the latches strike on the sides of the blade and offer no obstruction to the continued movement of the blade from between them. 95 As soon as the lower edge of the blade passes 100

out from between the latches they come together and are ready to catch and lock the blade the next time the switch is closed.

Figs. 4 and 5 show a modified form of a device embodying my invention, Fig. 4 showing the switch locked in the closed position, and Fig. 5 showing the parts in position to permit the switch to be opened, the operating rod being hooked in the eye 6 to pull the switch blade 4 out of the clip 2. In this modification the support 10 has pivoted to it a spring pressed latch 16 for holding the switch closed. This latch is provided with a hook or lug 17 for catching and holding a pin 18 on the switch blade 4 and thereby locking the switch closed. The latch is pivoted to swing in a plane parallel to the plane of movement of the blade 4 and is yieldingly held in either the locking position shown in Fig. 4 or in the releasing position shown in Fig. 5 by a coil spring 19, which has one end attached to the support 10 at the point 20 and the other end attached to the latch 16 at the point 21. The points 20 and 21 are so related to the pivot of the latch 16 that when the latch is in the position shown in Fig. 4 the spring 19 is above the pivot and is tending to hold the latch in the closed position, but when the latch is in the position shown in Fig. 5 the spring 19 is below the pivot of the latch and tends to hold the latch in the position shown. The latch is prevented from moving upward beyond the position shown in Fig. 4 by some suitable stop or shoulder, preferably on the support 10. When the switch is open, the latch is normally in the latching position, as shown in Fig. 4, ready to catch the pin 18 and hold the switch closed. As the switch is closed the pin 18 engages an extension 22 on the latch and thereby forces the latch down far enough to permit the switch to close, but not far enough to throw the spring 19 below the pivot of the latch. When the switch is fully closed, the latch is snapped up into position behind the pin 18 by the action of the spring 19. When the switch is to be opened, the latch 16 may be moved out of the way by pressing down on the latch with the operating rod until the spring 19 passes below the pivot of the latch, whereupon the spring 19 holds the latch in the position shown in Fig. 5. The latch is now out of the way and the switch is free to open. In order to make sure that the latch is automatically returned to latching position without attention or care on the part of the operator, I provide some means by which the latch is automatically thrown back into latching position by the movement of the switch blade. Various arrangements may be used for automatically throwing the latch back into latching position after the pin 18 is out of reach of the latch, but the preferred construction is that

shown, in which a resetting extension 23 on the latch is so shaped that when the latch is pushed down into the releasing position shown in Fig. 5, the pin 18 can move to the right away from the hook or lug 17 of the latch. As the switch opens and the pin 18 moves farther it engages a resetting cam or inclined surface 24 on the extension 23. The resetting cam 24 is so shaped that the movement of the blade out of the clip 2 causes the pin 18 to lift the latch until the spring 19 is above the pivot 16, whereupon the spring snaps the latch up into the latching position shown in Fig. 4, and the latch is ready to catch and hold the blade 4 as soon as the switch is closed. By the time the latch is lifted into latching position by the extension 23 the pin 18 is entirely out of reach of the latch, which cannot hinder further movement of the switch blade. The latch may for some reason remain in the position shown in Fig. 5 after the switch has opened. In order to positively force the latch into the latching position by the closing movement of the switch, I provide, on the extension 23, a secondary resetting surface 25 in position to be struck by the pin 18 as the switch is closed by the wooden operating rod 26. This secondary resetting surface is so proportioned that the pin 18 will positively lift the latch into the latching position as the switch blade goes into the clip 2, so that the latch is sure to catch and hold the pin 18 when the switch is fully closed.

By means of a locking device embodying my invention the switch is firmly locked against accidental opening; at the same time the locking device may easily be set in a releasing position in which it offers no hindrance to the opening of the switch; and before the switch is again closed the locking device automatically resumes the normal position in which it is free to catch and retain the switch blade when the switch is again closed.

A desirable embodiment of my invention is a form of device for stopping the blade of the switch in any predetermined position in such a manner that by a simple manipulation with the operating rod, the switch blade can be released and moved on into another position. This form of holding device may be applied to disconnecting switches in which the blade is horizontal when the switch is open and moves downward to close the switch, as for example in vertical double throw switches, in which the two contact jaws are in vertical alinement and the switch blade is pivotally mounted in a central clip midway between the two jaws and can be moved into engagement with either jaw at will. In disconnecting switches of this type the switch blade extends horizontally from the central clip when the switch is open, and there is a tendency for the

switch blade to swing down under the influence of gravity until it eventually touches the lower jaw and closes the circuit. In accordance with my invention, I provide a holding means which is normally in position to catch the blade of the disconnecting switch and prevent it from accidentally swinging downward into the lower jaw of the switch. The stop is so mounted that it 5 may be pushed out of the way by the operating rod and will remain out of the way and offer no obstruction as the switch blade is intentionally moved toward the lower contact. The stop offers no resistance to the 10 upward movement of the switch blade, but automatically swings out of the way as the switch blade is moved out of the lower jaw, and then swings back into position to prevent downward movement of the blade. 15 In the particular form of holding device for double throw disconnecting switches shown in the drawing the switch blade 27 of a double throw switch is pivotally mounted in a center clip 28 and can be swung upward 20 into engagement with the upper jaw or downward into engagement with the lower jaw. This form of double throw disconnecting switch is well known and neither the upper nor the lower jaw is illustrated in 25 the drawing.

In order to stop the blade in the horizontal position shown in Fig. 6, I provide a holding device comprising a frame 29 mounted immediately adjacent the center clip 28 and provided with pivots 30 on which arms 31 are pivotally mounted to swing in a plane transverse to the plane of movement of the switch blade 27. The arms 31 are provided with extensions 32 which can easily be caught by the operating rod when the arms are to be swung back out of the way. The arms are yieldingly biased to normal position, best shown in Fig. 7, by any suitable means, such as 35 springs 33 mounted in sockets or recesses in the frame 29 and pressing upon plungers 34 slidably mounted in the sockets. The thrust of the springs 33 is exerted upon the arms 31 through bell cranks 35 pivotally mounted on the arms 31. One end of each bell crank 35 is engaged by a plunger 34 and the other end actuates restraining members or stops 36 mounted upon pivots 37 on the arms 31 and normally in position to project 40 into the path of the blade 27. As a result of this construction the thrust of the springs 33 not only urges the arms 31 into the position shown in Fig. 7 but also tends to turn the holding members 36 about their pivots 37. The restraining members or stops 36 are provided with shoulders 38 and 39 which limit the upward and downward movement of the inner ends of the restraining members. The restraining members can turn 45 about their pivots to a limited extent inde-

pendently of the arms 31 and in the direction of the movement of the blade 27. The strength of the springs 33 is so related to the frictional resistance to movement of the blade 27 in the clip 28, that when the switch 50 is open and the switch blade is horizontal, as shown in Fig. 8, the inner ends of the holding members 36 are moved downward until the holding members are in the position shown in Fig. 8, and are held there by the 55 blade 27. The shoulders 39 prevent further rotation of the stops 36, and downward movement of the blade 27 is positively prevented unless the holding members 36 are in some way removed from the path of the 60 blade. When the blade is to be moved into engagement with the lower jaw one of the arms 31 as, for example, the right hand arm as shown in Fig. 9, is swung away from the 65 blade 27 by means of the wooden operating rod 26 until the inner end of the holding member 36 passes out from underneath the blade 27, whereupon the spring 33 quickly rotates the holding member 36 about its 70 pivot and raises the inner end of the holding member until stopped by the shoulder 38, as shown in Fig. 9. By this movement the inner end of the holding member 36 is 75 lifted above the lower edge of the blade and into alignment with the side of the blade 27. 80 When the arm 31 is released from the operating rod 26, the arm cannot swing back into its normal position because the inner end of the holding member 36 strikes the 85 side of the blade and the arm is held against further movement toward the blade, in a 90 position in which the only resistance offered by the holding member 36 to the downward movement of the blade 27 is the friction of the inner end of the holding member against 95 the side of the blade. The other arm 31 is 100 then swung away from the blade, whereupon the inner end of the other holding member 36 is also swung upward until it is above the 105 lower edge of the blade and in alignment 110 with the other side of the blade. As a result of these manipulations the blade 27 is now gripped between the two holding members, 115 which now engage the sides of the blade and offer only frictional resistance to downward movement of the blade, instead of projecting into the path of the blade and acting as positive stops. With comparatively slight effort the blade 27 can now be swung downward from between the holding members 120 125 130 135 140 145 150 155 160 165 170 175 180 185 190 195 200 205 210 215 220 225 230 235 the arms 31 apart and passes through between them with comparatively slight resistance. In all cases the holding members 36 automatically swing into the normal holding position as soon as the blade passes from between them.

My invention may be embodied in many other forms than those described and therefore I do not wish to limit myself to the precise arrangement disclosed but aim in the appended claims to cover all modifications within the spirit and scope of my invention.

What I claim as new and desire to secure by Letters Patent of the United States, is,—

1. A holding device for switches comprising a holding member yieldingly biased when in normal position to lock the switch, means operative upon movement of said holding member into its releasing position to restrain said holding member in said releasing position while the switch is still closed, and means controlled by the switch for automatically returning said holding member from releasing position to normal position prior to the closing of the switch.

2. A locking device for electric switches comprising a spring pressed latch normally in position to engage a movable member of the switch, restraining means for said latch rendered operative by movement of said latch into releasing position to restrain said latch in said releasing position while the switch is still closed, and means whereby the movable member of the switch automatically controls the return of said latch to normal position.

3. A locking device for electric switches comprising a latch biased when in normal position to lock the switch closed, restraining means rendered operative to hold said latch in releasing position by movement of said latch from normal position to releasing position, and means actuated by the opening movement of the switch for automatically returning the latch to normal position.

4. A locking device for switches comprising a latch biased to locking position, and restraining means rendered operative by movement of said latch into releasing position to hold said latch in releasing position as long as the movable member of the switch is in engagement with said latch.

5. A locking device for switches comprising a latch biased to locking position, and a pawl pivotally mounted on said latch and biased to move into position to catch and hold said latch when said latch is moved into releasing position, said latch being held in releasing position by said pawl while the movable member of said switch is still in closed position.

6. A locking device for switches comprising a latch pivotally mounted in position to lock the switch, a pawl pivotally mounted on said latch, a shoulder on said latch for

stopping said pawl in position to hold said latch in releasing position, and a spring for yieldingly forcing said pawl toward said shoulder and said latch toward latching position.

7. In an electric switch, the combination with a movable switch member, of a locking device comprising a latch normally biased to lock said member, restraining means co-operating with said latch and said member and operative by movement of said latch to restrain said latch in releasing position while the switch is closed, and means for returning said latch automatically to normal position prior to the closing of the switch.

8. In an electric switch, the combination with a movable switch member, of a locking device comprising a latch for said member, restraining means rendered operative by movement of said latch into releasing position while the switch is closed to hold said latch in releasing position, and means controlled by said switch member for automatically returning said latch to latching position as said member is moved to open the switch.

9. In an electric switch, the combination with a movable switch member, of a locking device comprising a latch operative when in normal position to lock said member in switch closing position, means co-operating with said latch to restrain it in inoperative position when moved into said inoperative position while the switch is closed, and means controlled by said switch member and co-operating with said latch to automatically return said latch to operative position during the opening of the switch.

10. In an electric switch the combination with a movable switch blade, of a locking device comprising a latch normally biased to engage said blade, a pawl pivoted on said latch with its end projecting into the path of said blade when the latch is in normal position, and means for yieldingly forcing said pawl into position to bring its end against the side of said blade when said latch is moved into releasing position, whereby said pawl holds said latch in releasing position.

11. In an electric switch, the combination with a movable switch blade, of a locking device comprising two latches mounted on a common pivot and biased to move toward each other to engage opposite sides of said blade, and a pawl mounted on each latch near said pivot with its end projecting into the path of movement of said blade and biased to move away from said pivot along the side of said blade when either of said latches is moved into releasing position whereby said latches are held in releasing position while the switch is closed.

12. A locking device for switches comprising a support having a recess, a latch

pivoted to said support at one side of said recess, a pawl pivoted to said latch at a point adjacent said recess to extend toward the pivot of said latch, said latch having a shoulder to limit movement of said pawl away from said recess, and a compression spring mounted in said recess to engage said pawl between its pivot and the pivot of said latch and thereby force said pawl 10 toward the shoulder on the latch and said latch toward latching position.

13. A device for holding a switch blade in a predetermined position, comprising an arm pivoted to swing in a path transverse 15 to the path of the switch blade and biased to move toward said blade, and a restraining member pivoted on said arm to project into the path of the blade and to have a limited movement relative to said arm in the same direction as said blade, said member being biased to move toward said blade 20 when said blade is in its predetermined position.

14. A device for holding a switch blade 25 in a predetermined position, comprising a holding member mounted to move in a path transverse to the path of the switch blade and yieldingly biased to move toward the blade into holding position, and a restraining member moveably mounted on said hold-

ing member to project into the path of the blade and to have a limited movement relation to said holding member in the same direction as said blade, said restraining member being biased to move toward said 35 blade when said blade is in its predetermined position.

15. A device for holding a switch blade in a predetermined position comprising a holding member yieldingly mounted to permit 40 said blade to move into said position and to automatically prevent movement of said blade out of said position, restraining means coöperating with said blade and said holding member when said blade 45 is in said predetermined position to automatically restrain said holding member when it is moved into position to release said blade and to hold said member in releasing position until said blade is 50 moved out of said predetermined position, and means for returning said member automatically to normal position after said blade is removed.

In witness whereof, I have hereunto set 55 my hand this 21st day of June, 1912.

HENRY G. FRENCH,

Witnesses:

BENJAMIN B. HULL,
HELEN ORFORD.
